UNITED STATES PATENT OFFICE.

JAMES M. MARRS AND HIRAM W. PEERY, OF ALBANY, MISSOURI.

GATE.

SPECIFICATION forming part of Letters Patent No. 391,418, dated October 23, 1888.

Application filed August 14, 1888. Serial No. 282,725. (No model.)

To all whom it may concern:

Be it known that we, JAMES M. MARRS and HIRAM W. PEERY, citizens of the United States, residing at Albany, in the county of 5 Gentry and State of Missouri, have invented new and useful Improvements in Gates, of which the following is a specification.

The invention relates to improvements in gates, the objects being to provide means where- 10 by the weight of the gate may be caused to be supported by an adjacent fence-post, whereby the gate may be raised and supported vertically to permit of the passage of hogs and sheep therebelow, whereby sagging may be remedied, 15 and whereby the gate may be caused to swing automatically either to or from the latch-post; and it consists in the construction and novel combination of parts, hereinafter described, 20 illustrated in the accompanying drawings, and 25 pointed out in the appended claims.

In the drawings, Figure 1 is a perspective view of a gate and a portion of a fence, illustrating the invention. Fig. 2 is a view of the hinge-post and adjacent end of the gate. Fig. 25 3 is a view of the latch-post and the end of the gate adjacent thereto. Fig. 4 is a plan view of the gate, hinge-post, and latch-post.

Referring to the drawings by letter, A designates a gate composed of the pairs of end 30 bars, *a a*, and the rails *a'*, having their ends bolted or otherwise secured between the members of said pairs.

B is the hinge-post, and C the latch-post, the latter of which has the bar *c* secured to it on 35 the side toward which the gate opens through the end blocks, *c'*, forming the open space *c''* between the said post and bar for the engagement of the latch, hereinafter described.

c'' is a vertical stop-bar secured to the inner 40 face of the latch-post, adjoining the edge opposite the bar *c*.

B is the hinge-post, standing out of alignment with the fence on the side thereof opposite the bar *c*, and having secured in its upper 45 portion the eyebolt *d*, with vertical edges, and in its lower portion the eyebolt *d'*, with horizontal edges, the said eyebolts being in the side of the post parallel with the fence.

E is a vertical metal hinge-rod having a bearing at its lower end in the eyebolt *d'* and a transverse stop-pin, *e*, passing through an

opening in it below said bearing, and also a stop-pin, *e'*, passing through an opening in it a suitable distance above said bearing.

F is a hinge-sleeve secured to the adjacent 55 end bar of the gate and surrounding the rod above its bearing, and *f* is a movable washer on said rod below the sleeve.

The upper end of the rod *E* stands to the inner side of the eyebolt *d*, and has engaged to 60 it, just below its flattened head *g*, the looped end of the strong reflexly-bent wire *G*, the loop at the opposite end of which is engaged in a transverse notch, *g'*, made at a proper distance in the farther side of the nearest fence-post *g''*. The said wire, consisting of more 65 than one strand, can be readily taken up or let out to adjust the angle at which the rod *E* stands.

H is the latch sliding upon the middle gate-rail and passing between the adjoining end bars to engage between the latch-post and bar *c*, and *h h'* are guide-levers pivoted at their upper ends to the opposite sides of the latch and at their lower ends to the opposite sides of the 75 lowest gate-rail. *h h'* are vertical stop-bars secured to the opposite sides of the gate-rails to the inner side of the guide-lever. The inner end of the latch is connected by a wire, *i*, with the end of the lower arm of a double- 80 armed lever, *I*, pivoted upon the gate-rail second from the top and with its upper arm projecting above the gate and accessible from both sides thereof. The motion of the said lever is limited in each direction by the retaining- 85 staple *i'*, secured to the top rail of the gate.

J is a two-stranded wire, the front bend of which rests in a transverse groove, *j'*, in the front edges of the guide-levers *h*, below their pivotal points on the lowest gate-rail and in 90 the bar connecting the lower ends of the said levers, the rear bend of said wire engaging against the outer side of the vertical hinge-rod *E* near the upper end thereof. The wire passes between the adjacent end bars of the 95 gate. The front part of the gate is thus held up or supported by said rod, the latter being supported from the fence-post by the wire *G*.

K is a lever pivoted at its lower end at a proper point to the gate-rail second from the 100 top and provided at a point about midway of its length with the swinging arms *k*, having

their lower portions bifurcated, and the grooved-edged rollers L journaled between the arms of the bifurcations thereof. The strands *j* of the wire J rest in the peripheral grooves 5 of said rollers and pass between the arms of the bifurcations above the rollers. A series of adjusting-openings, *m*, are made in the top rail adjacent to the lever K and are adapted to receive the pin M, which forms a stop for 10 said lever. It is evident that by moving the lever K toward the latch-opening the rollers will lift and tighten the strands *j* of the wire J, which can be held thus tightened by inserting 15 said pin M into the proper opening, *m*, in rear of the lever. The wire J, being in two strands with connected ends, may readily be taken up or let out to lift more or less the free end of the gate.

It is evident that as the wire G supports the 20 rod E from the fence-post *g*, and as the wire J supports the bottom rail of the gate from the said rod, the basis of support for the weight of the entire gate must be the said post, however slack the said wires may be if the bottom 25 of the gate does not touch the ground. By slackening the wire G the upper part of the rod E will incline outward from the hinge-post, and the gate will consequently swing open when the latch is drawn. By tightening 30 said wires the upper end of the rod E can be drawn nearer to the hinge-post than its bearing, and the gate will consequently swing toward the latch-post. By removing the stop-pin *e*, lifting the gate vertically upward, and 35 again inserting said pin below the hinge-sleeve F and washer *f*, the gate can be kept raised for the passage of hogs, sheep, &c., underneath.

As the lever K by being moved outward 40 tightens the wire strands *j* on the rollers L and raises the outer or free end of the gate, all sagging can be remedied by so moving said lever. The said motion also turns the upper ends of the guide-levers *h* toward the latch-post and 45 increases the force with which said levers, actuated by the wire J, will return the latch outward after being drawn inward by the releasing-lever I.

As the open space *c* between the latch-post 50 and bar *c* extends nearly their entire length, the latch will engage, however high the gate may be raised.

Having described our invention, we claim—

1. The combination, with a gate, of a hinge- 55 post having an eyebolt secured in the side fac- ing of the gate near its top and an eyebolt secured in said side near its bottom, a vertical hinge-rod having a bearing in the lower eye-

bolt, the gate being hung on said rod, and a wire attached to the hinge-rod near its top, 60 passing thence through the upper eyebolt of the hinge-post, and having its outer end attached to the nearest fence-post, the said wire being adjustable in length, substantially as specified. 65

2. The combination, with the hinged gate, the two-stranded wire attached at its front end to the lower front portion of the gate and at its rear end to the upper part of the hinged end of the gate, the said wire being adjustable 70 in length, the lever pivoted at its lower end to the gate, the rollers journaled in said lever and having grooves, in which the corresponding strands of the wire rest, and the stop-pin adapted to fit behind said lever in any one of the adjusting-openings in the top rail of the gate, 75 substantially as specified.

3. The combination, with the gate, the two-stranded wire J, the lever K, and the grooved rollers L, of the hinge-post, having attached 80 the eyebolts *d* and *d*', the hinge-rod having a bearing in the eyebolt *d*', the wire G, attached to the hinge-rod, and the fence-post *g*, having the outer end of said wire attached, substantially as specified. 85

4. The combination of the hinge-post having a bearing eyebolt near its lower end, the hinge-rod having a bearing in said eyebolt and attached loosely to the hinge-post, the stop-pin passing through an opening in said rod below 90 said eyebolt, and the stop-pin passing through an opening in the hinge-rod a suitable distance above the eyebolt, with the gate, the hinge-sleeve surrounding the hinge-rod above its bearing and secured to the adjacent end of the 95 gate, substantially as specified.

5. In a gate, the combination of the sliding latch, the double-armed lever pivoted to the gate, with its upper arm projecting thereabove and its lower arm connected with the inner end 100 of the latch by a wire, the guide-levers pivoted at their lower ends to the bottom rail and at their upper ends to the latch, and the wire J, attached to said levers below their pivotal points at its front end and at its rear end to 105 the hinge-rod on which the gate is hung, substantially as specified.

In testimony that we claim the foregoing as our own we have hereto affixed our signatures in presence of two witnesses.
